Charles H. Mackie
ATTORNEY

UNITED STATES PATENT OFFICE

CHARLES H. MACKIE, OF BROOKLYN, NEW YORK, ASSIGNOR OF ONE-HALF TO
AUGUSTUS L. MEROLLE, OF BROOKLYN, NEW YORK

CIGARETTE PACKAGE

Application filed August 8, 1930. Serial No. 473,906.

This invention relates to a cigarette package, and an object of the invention is to provide an attractive form of package in which cigarettes may be packed and marketed and which will include simple, practical and efficient means by which the cigarettes may be easily and quickly discharged one by one from the package.

A more specific object is to provide a package having a cigarette discharging device built thereinto adapted for discharging the cigarettes one at a time as the result of a simple manual manipulation of a part of the package.

15 A further specific object is to provide a package having a rotary trap door formed as a part of one of the walls of the package manually rotatable into and out of a position discharging a cigarette from within the pack-

20 age. A further specific object is to provide means normally holding said trap door closed.

Other objects and aims of the invention, 25 more or less specific than those referred to above, will be in part obvious and in part pointed out in the course of the following description of the elements, combinations, arrangements of parts and applications of 30 principles constituting the invention; and the scope of protection contemplated will be indicated in the appended claims.

In the accompanying drawing which is to be taken as a part of this specification, and 35 in which I have shown merely a preferred form of embodiment of the invention:—

Fig. 1 is a perspective view of a cigarette package constructed in accordance with this invention, a portion being broken away to 40 illustrate a portion of the trap door operating device.

Fig. 2 is a similar perspective view of the package but taken from a different angle and showing the rear side of the package.

45 Fig. 3 is a transverse sectional view substantially upon the plane of line III—III of Fig. 1 and showing the trap door closed.

Fig. 4 is a sectional view similar to Fig. 3 but illustrating the parts as they appear 50 when the trap door is open.

Fig. 5 is a front elevational view of a package similar to that illustrated in the previous figures but showing a modified form of device for operating the trap door, and

Fig. 6 is a transverse sectional view similar to Fig. 3 but showing the structure appearing in Fig. 5.

Referring to the drawing for describing in detail the structure as illustrated therein, it will be seen that the package is of ordinary 60 rectangular contour of the general proportions as common to ordinary cigarette packages adapted for containing a dozen or more of cigarettes. The package is formed of paper or cardboard of appropriate thickness and 65 consists of top and bottom walls 1 and 2, opposite end walls 3 and 4 and front and rear walls 5 and 6. The paper or cardboard from which these walls are formed may be cut, folded, and gummed together in any appropriate manner, and it will be understood that a separate covering or wrapper of paper, as indicated at 7, either transparent or otherwise, may be placed about the walls to more 70 effectually seal the contents if desired.

75 In the front wall as 5 there is formed an opening 8 of suitable size to permit lateral discharge of cigarettes from within the package. Within this opening is a semi-cylindrical trap door 9 pivoted at its opposite ends 80 as at 10 and 11 upon the end walls 3 and 4 so as to be freely oscillatable between open and closed positions. This trap door is of an appropriate size to receive and support within its concaved side one of the cigarettes as 85 11, approximately as indicated, and is adapted, when swung from its closed to its open position, to move around behind the supported cigarette and to thereby expose that particular cigarette exteriorly of the package 90 so that said cigarette will drop out free of the package.

Any suitable means may be provided for oscillating the trap door. For this purpose the drawing Figs. 1 to 4 suggests the use of 95 a pull-thread as L connected with the door and extending therefrom into connection as at 12 with the lower edge of a finger flap G pivotally mounted as a part of the rear wall 6 of the package. A resilient tension member, 100

such for instance as a small strip of rubber as H indicated, is connected with the door by one end with a wall, as 3, of the package at its opposite end for urging the door always to closed position.

When a cigarette is to be removed from a package the operator simply bends the flap G outwardly with his finger from the position Fig. 3 to the position Fig. 4, thereupon 10 swinging the door contrary to the pull of the member H and thus discharging the cigarette.

It is noted that the tension member extends about the door in a relatively clock-wise direction while the pull-string extends in a relatively contra-clockwise direction.

In the modification Figs. 5 and 6 it is intended that the door shall have a sufficiently tight fit with adjacent portions of the package so as to be held by friction in any position to which it is manually moved, and that a friction element as 13 may be provided upon the door adapted to be engaged by the pad of an operator's finger for swinging the door 20 either open or closed as desired. In this structure the friction element 13 is adapted to rub against the upper surface of the bottom wall 2 of the package, as at 14 for thereby furnishing the desired frictional engagement 25 between the door and the rest of the package to maintain the door in any position to which it is moved.

By oscillating the door the cigarettes may be discharged from the interior of the package one after the other in the same manner as in the previous figures.

As many changes could be made in this construction without departing from the scope of the invention as defined in the following claims, it is intended that all matter contained in the above description, or shown in the accompanying drawing, shall be interpreted as illustrative only and not in a limiting sense.

Having thus described my invention, what I claim as new and desire to secure by Letters Patent is:—

1. A cigarette package comprising confining top bottom side and end walls adapted to contain a supply of cigarettes, one of said walls having an opening therethrough of a size to permit lateral discharge of a cigarette therethrough a trap door positioned within said opening concaved on its inner side adapted to receive a cigarette therein, means by which said trap door is pivotally mounted to swing for disposing said cigarette exteriorly of the package, and operating means for said trap door including a finger flap pivotally mounted upon a wall of the package remote from the door and a flexible thread operatively connecting said flap with said door so that pivotal movement of said flap will draw upon the thread and swing the door in one direction.

2. A cigarette package comprising confining top bottom side and end walls adapted to contain a supply of cigarettes, one of said walls having an opening therethrough of a size to permit lateral discharge of a cigarette therethrough, a trap door positioned within said opening concaved on its inner side adapted to receive a cigarette therein, means by which said trap door is pivotally mounted to swing for disposing said cigarette exteriorly of the package, resilient means urging the trap door to closed position, a movable finger piece arranged at an opposite wall of said package, and connections between the trap door and said finger piece operable to swing the trap door by movement of the finger piece. 70

3. A cigarette package comprising confining top bottom side and end walls adapted to contain a supply of cigarettes, one of said walls having an opening therethrough of a size to permit lateral discharge of a cigarette therethrough, a trap door positioned within said opening concaved on its inner side adapted to receive a cigarette therein, means by which said trap door is pivotally mounted to swing for disposing said cigarette exteriorly of the package, resilient means extending about the trap door in one direction and engaging an adjacent wall of the package operable to swing the trap door toward closed position, a movable finger piece arranged at another wall of the package, and a flexible thread extending about the trap door in an opposite direction and engaging said finger piece to swing the trap door against the tension of said resilient means by movement of said movable finger piece. 80

4. A cigarette package comprising confining top bottom side and end walls adapted to contain a supply of cigarettes, one of said walls having an opening therethrough of a size to permit lateral discharge of a cigarette therethrough, means arranged at said opening operable to discharge a cigarette through said opening, and an operating device for said discharge means including an actuating member arranged at a relatively opposite side wall of the package and connections extending therefrom across the package to the discharge means. 90

In testimony whereof I affix my signature.

CHARLES H. MACKIE.
